UNITED STATES PATENT OFFICE

FREDERICK J. HOLMES, OF DETROIT, MICHIGAN

ENGINE

Application filed February 27, 1930. Serial No. 431,958.

This invention relates to an internal combustion engine of that type utilizing spaced annular series of cylinders, the cylinders of each series alining with the corresponding 5 cylinders of the opposed series.

It is old, in engines of this type, to connect the corresponding pistons in the opposed cylinders by rods and to utilize these rods for transmitting motion to a cam carried by a 10 shaft rotatable between the cylinders of the opposed series.

In engines of the type mentioned considerable difficulty has been encountered because, due to the excessive resistance from the 15 driven cam, the connecting rods have been subjected to torque and lateral strains which have distorted the rods, pushed them out of line, and subjected the pistons to such lateral or radial strains as to cause them to bind 20 excessively on the walls of the cylinders. Consequently the cylinders and pistons have been unable to stand up under the strains and it has been impossible to produce a practical engine.

It is an object of the present invention to 25 provide means, in an engine of the type mentioned, whereby distortion of the connecting rods by twisting or bending is eliminated by the use of a floating connecting rod having a guide.

It is also an object to so connect the rods 30 to the pistons that any radial movements of the rods due to wear, etc., will not produce a corresponding movement of the pistons but said pistons, on the contrary, will be relieved 35 at all times from radial strains and will reciprocate freely during the operation of the engine without causing excessive wear.

With the foregoing and other objects in 40 view which will appear as the description proceeds, the invention resides in the combination and arrangement of parts and in the details of construction hereinafter described and claimed, it being understood that changes 45 in the precise embodiment of the invention herein disclosed may be made within the scope of what is claimed without departing from the spirit of the invention.

In the accompanying drawings the preferred 50 form of the invention has been shown. In said drawings,

Figure 1 is a longitudinal section through an engine having the present improvements combined therewith.

Figure 2 is an irregular section through the motor taken substantially on the line 2-2, 55 Figure 1.

Figure 3 is a plan view of one end portion of a connecting rod, adjacent parts being shown in section.

Referring to the figures by characters of 60 reference 1 and 2 designate metal drums provided at their centers with bearings 3 in which is journaled a shaft 4.

Each of the drums is provided with annular series of parallel cylinders 5. The two 65 drums are spaced apart and can be held against rotation by any suitable means. Interposed between the drums and fixedly secured to shaft 4 is a cam 6.

The cylinders in each drum are in alignment with the corresponding cylinders of the opposed drum and slidably mounted in each cylinder is a hollow piston 7 in the open end portion of which is mounted a diametrical pin 8. As shown in Figure 3 75 70 the pin 8 is angular in cross section and it is to be understood that all of the pins are disposed radially relative to the shaft 4.

The pistons in the opposed alining cylinders are connected by rods 9. These rods 80 are preferably T-shaped in cross section and each rod is provided at its ends with angular openings 10 through which pins 8 extend. An extension 11 is carried by the middle portion of each rod and has means, 85 such as a roller 12, for operatively engaging the cam 6.

It is to be understood that each cylinder is to be equipped with suitably operated valves 13 and 14 for controlling the intake 90 of fuel and the exhaust of spent gases. Suitable timing means, not shown, can be provided and it is designed to have the charges in the several cylinders explode successively so as to operate the pistons in rapid 95 succession.

During the reciprocation of the pistons motion will be transmitted therefrom through the rods 9 to the cam and this cam will be rotated so as to drive shaft 4. A cer- 100

tain amount of radial movement of the rods independently of the pistons is permitted because of the sliding engagement of the pins 8 by the rods 9. Consequently the pistons 5 will be unaffected by such radial movement of the rods and will not be caused to thrust radially against their cylinders.

For the purpose of resisting radial movement of the rods and bending or twisting 10 thereof, each of the rods is provided with guiding means. This guiding means includes plates 15 suitably secured to the adjacent drum close to the open end of the cylinder. Arms 16 extend from the plates to opposite sides of the rod to be guided and journaled in the arms is a roller 17 adapted to extend transversely of and to engage the outer surface of the rod 9. A side roller 18 is carried by each arm 16 and these side rollers 20 engage the sides of the rod 9. Thus it will be seen that any tendency of the rod to bend in any direction will be resisted by the rollers.

It will be apparent that by providing floating connecting rods, it becomes possible to 25 produce a motor of the type herein described capable of operating at very high speeds. Such a motor will also be able to stand up for a long period of time because the working parts are not subjected to excessive strains 30 due to distortion of the connecting rods.

As shown in Figure 3 the connecting rod is capable of lateral movement relative to its pins as well as movement lengthwise of the pins. Thus the rod is free to shift both 35 laterally and radially of the pistons to compensate for wear and distortion and to allow the pistons to remain in alignment. Furthermore the piston rod 9 is always parallel with the path of movement of its pistons so that 40 the lines of force remain parallel with the rod and no distortion will result as in structures wherein the rods are obliquely disposed relative to the pistons at any or all times.

What is claimed is:

45 1. An internal combustion engine including spaced alining cylinders, pistons therein, a rod having a slidable connection with each of the pistons, guiding means for holding the rod against outward and lateral buckling, and power transmitting means operatively connected to the rod.

2. An internal combustion engine including spaced alining pistons, a rod connected at its ends to the pistons for sliding movement 55 radially of the pistons along either of two intersecting lines in each piston, a shaft, and means operated by the reciprocation of the rod for driving the shaft.

3. An internal combustion engine including opposed alining cylinders, a piston in each cylinder, an angular pin disposed diametrically within each piston, a connecting rod mounted at its ends on the respective pins for sliding movement longitudinally 60 and transversely of the pins, a shaft, and

means operated by the rod when reciprocated for driving the shaft.

4. An internal combustion engine including opposed alining cylinders, a piston in each cylinder, an angular pin disposed diametrically within each piston, a connecting rod slidable at its ends on the respective pins to slide longitudinally and transversely of the pins, means for holding the rod against outward and lateral bending while reciprocating with the pistons, a shaft, and means for transmitting motion between the shaft and the rod. 70

5. An internal combustion engine including spaced alining cylinders, a piston in each cylinder, a diametrically disposed pin in each piston, a rod connecting the pistons and mounted at its ends on the pins to slide longitudinally of the pins and transversely thereof and of the path of movement of the pistons, anti-friction guides for the rod, and means for transmitting motion from holding the rod against outward and lateral bending. 80

6. An internal combustion engine including spaced alining cylinders, a piston in each cylinder, a diametrically disposed pin in each piston, a rod connecting the pistons and mounted at its ends on the pins, to slide longitudinally of the pins and transversely thereof and of the pistons, separate guides connected to the respective cylinders for holding the rod against outward and lateral distortion, a shaft, and means for transmitting motion between the shaft and the rod. 85

7. An internal combustion engine including opposed aligning cylinders, pistons guided therein for right-line movement, guiding means between the cylinders, a piston rod mounted for right-line reciprocation in the guiding means and connections between the piston rod and pistons permitting independent shifting of the ends of the rod along intersecting diametrical lines in the pistons to which they are connected. 100

8. An internal combustion engine including opposed aligning cylinders, pistons guided therein for right-line movement, guiding means between the cylinders, a piston rod mounted for right-line reciprocation in the guiding means and connections between the piston rod and pistons permitting independent shifting of the ends of the rod along intersecting diametrical lines in the pistons to which they are connected, said connections each including a diametrically disposed pin secured in a piston and angular in cross section, there being a slot in the end portion of the rod through which the pin extends, the walls of the slot and the pin cooperating to prevent independent movement of the rod and pin in the direction of the length of the rod but permitting sliding movement of the rod transversely of the pin and longitudinally thereof. 115

9. An internal combustion engine including opposed aligning cylinders, pistons mounted for reciprocation therein, a rod connecting the pistons and movable relative thereto along intersecting diametrical lines in the pistons, said rod and the pistons being disposed along lines parallel with the longitudinal axis of the aligning cylinders.
10. An internal combustion engine including opposed aligning cylinders, pistons guided therein for right-line movement, guiding means between the cylinders, a rigid piston rod mounted for right-line reciprocation in the guiding means and direct connections between the piston rod and pistons permitting independent sliding of the ends of the rod along intersecting diametrical lines in the pistons to which they are connected.
11. An internal combustion engine including opposed aligning cylinders, pistons mounted for reciprocation therein, a rigid rod directly connecting the pistons, each end being slidable relative to the adjacent piston along intersecting diametrical lines in the piston, said rod and the pistons being disposed along lines parallel with the longitudinal axis of the aligning cylinders.
12. An internal combustion engine including opposed series of fixedly connected cylinders, pistons within the respective cylinders, a cam, bars projecting into opposed pistons of the two series, means connecting each bar to its pistons for radial movement in the pistons along two intersecting lines, and antifriction devices engaging the bars to hold them against outward radial and lateral displacement.
13. An internal combustion engine comprising a shaft, two annular series of cylinders arranged around said shaft, corresponding cylinders of the respective series being axially aligned, a piston within each cylinder, a bearing element carried by each piston, a rigid bar directly connected at its ends with the bearing elements of each related pair of pistons for lateral movement relative to the pistons in a direction radially with respect to said shaft and also for lateral movement in a direction at right angles to the direction of the first mentioned movement, a cam on said shaft, and a connection between each bar and said cam whereby reciprocation of the pistons and the bars produces relative rotation between the cylinders and the shaft.
14. An internal combustion engine as set forth in claim 13 including guide means for the bars to resist lateral thrust imposed on the bars by the reaction of the connections of the bars with the cam.
15. In testimony that I claim the foregoing as my own, I have hereto affixed my signature.
- FREDERICK J. HOLMES.
